BAG EMPTYING MACHINE

Vernon J. David, Durham, Kans.

Application May 20, 1952, Serial No. 288,987

10 Claims. (Cl. 214—314)

This invention relates to a machine or mechanical device for transferring the contents of one container into another container, receptacle and the like.

More particularly, this invention relates to a machine which may be used advantageously for emptying conventional bags or sacks of different sizes and shape, such as are used in the storing and transporting of livestock feeds and other analogous flowable materials.

The principal object of the present invention is the provision of a machine of the indicated character for the convenient handling of bags or sacks for the stated purpose, and affording the following advantages.

To enable the handling of bags or sacks of different sizes as to length and width in a tilttable container body having a spout and discharge control gate. The container body is designed and adapted to keep each bag or sack from slipping or sagging relative to the body thereby preventing the bag or sack from fouling or jamming the gate as the body is moved from an upright loading position into an inclined discharging position and through the complete emptying operation.

The contents of a bag or sack may be conveniently discharged by means of the spout and gate which prevent the material from spilling or overflowing, while the rate of flow of the material may easily be regulated at the will of the user.

The discharge control gate is placed at an angle to the longitudinal axis of the body to provide the user with maximum visibility of the pail or container being filled; to provide improved inherent agitating action of the gate as it is opened or closed; and to provide proper means for operating additional agitation means to agitate the material as it leaves the open end of a bag or sack or as contained in the enclosed tubular spout, thereby assuring steady outflow of the material under control of the gate.

The container body of the machine is mounted on a base, that each bag or sack may be placed in, and the body together with the bag or sack may be tilted into a position for the discharge of the bag or sack contents with a minimum amount of manual effort.

The machine body may be adjusted to the desired angles in either a vertical or horizontal plane and in regard to the distance of the discharge spout end, in the discharging position, and the other, or bottom end, in the loading position, to the base and to the mount post. A vertical adjustment is provided on the mount post. The aforesaid adjustments are designed to meet the requirements of different sizes and weights of bags or sacks, different sizes of pails or containers, proper and convenient loading of the bags or sacks, proper holding action of the bars, proper flow of the material being discharged, and proper center of gravity, and may be made independently or in different combinations to meet the aforesaid requirements.

The machine is provided with novel means which in addition to making it possible to turn the container body into different angular positions for loading and emptying

operations and to obtain different elevations of the container body, also provide easy portability through the utilization of a circular base.

With the foregoing, other objects, benefits and advantages will appear when the following specification is read in conjunction with the accompanying drawings, in which:

Fig. 1 is a vertical sectional view of a machine constructed in accordance with the present invention, the container body of the machine being shown in its loaded position in full lines and in a discharging position in dotted lines.

Fig. 2 is a rear elevational view of the machine with the parts in the relation shown in Fig. 1.

Fig. 3 is a view similar to Fig. 1 showing the container body in a discharging position, but turned one hundred and eighty degrees from the discharging position shown in Fig. 1.

Fig. 4 is a rear elevational view of the machine with the container body in its discharging position.

Fig. 5 is an enlarged fragmentary vertical sectional view showing certain parts of the stand on which the container body is mounted.

Figs. 6, 7, and 8 show different types of barbs used to keep a bag from slipping or sagging, Fig. 7 being a sectional view taken on the line 7—7 of Fig. 6.

Fig. 9 shows a portion of the container body and the adjustable and removable plate to adapt the body for bags or sacks of different size as to length.

Fig. 10 is a fragmentary detail sectional view.

Generally stated, the machine comprises a container body 10 with discharge control means, and a stand 11 on which the body 10 is mounted for movement between a loading position and a discharging position. The body 10 is designed and adapted to accommodate conventional filled bags or sacks of different sizes and shapes.

The body 10 is of troughlike construction. It is constructed from suitable material which may be sheet metal as shown in the present instance. The body 10 is substantially U shape in cross section. It has a permanent sloping rear end wall 12 having corrugations or channels 13 and 14 respectively, the channels 13 being at the sides and diverging rearwardly, and the channel 14 being disposed centrally. It is understood that the wall 12 serves as the bottom of the body 10 when the latter is in the loading position, and that the channels 13 and 14 strengthen the wall 12 and may serve as feet for the body. The channels 13 also accommodate the usual protruding ears or corners of the bottom end of a loaded bag. A bail or other handle 15 is secured to the wall 12 for manipulating the body 10.

The front end of the body 10 has formed integrally therewith, or has secured thereto, a spout 16 which is tapered and tubular, as shown most clearly in Figures 2 and 4. The spout has spaced guides 17 thereon. A gate 18 is slideable in the guides 17 into an open and closed position. A bail or other handle 19 is secured to the gate for manipulation. A scraper 20 is secured to the spout 16 in cooperative relation to the gate 18. Upon movement of the gate the scraper keeps the inside surface of the gate clean. Chains 21 are provided. Each chain has one end connected with the body 10, as at 22, and its opposite end connected with the gate 18, as at 23. The chains 21 constitute additional means for agitating the material as it is being discharged from the open end of a bag or sack, by manipulating the gate with the handle 19. This assures a steady outflow of the material as the bag or sack is being emptied. The point of attachment of the chains 21 also limits the opening movement of the gate 18 and prevents it from being separated from the spout 16. The size of the spout is such as to accommodate most common size bags. However an extension 6, Fig. 10, may be attached to lengthen the tubular con-

struction, preventing the spilling or overflowing of material when unusual size bags are used. The gate controls the rate of outflow of the material at the will of the user.

In order to prevent a bag or sack from sagging or slipping forward as it is being emptied, and jamming and fouling the gate 18, the body 10 and the spout have distributed on the insides thereof a multiplicity of suitably directed burrs or barbs 24.

The barbs may be formed integrally with the body and spout. The points of the barbs are directed in a generally rearward direction, with the points at the sides of the body directed rearwardly and toward the center of the body in a manner such as to direct the points in a direction roughly parallel to the movement of the sack or bag as it is raised slightly higher than the wall 12 and then placed with a slight downward movement into the body and down on the wall 12. The center-ward direction of the barbs is progressively changed from the sides toward the center until near and at the center the barbs point in a direction near parallel with the longitudinal axis of the body. The points simultaneously and progressively change also in regard toward vertical direction, with the points being near parallel to the horizontal axis of the body near the sides and increasing toward the center.

The proper arrangement of the directions and placement of the barbs, together with the shielding effect of the hemispherically or similarly mounted barbs prevent the snagging or catching with consequent damage to the bag as it is placed in the body 10, and at the same time effect a positive angle of attack of the barb points toward the movement of the bag toward the gate. The barbs are arranged to hold the bag at the sides as well as the underside to eliminate slipping or sagging and readily release their hold when the body is returned to its upright loading position, or when the bag is pulled manually in a direction away from the gate for the removal of the bag from the machine.

The stand 11 comprises a circular base 25 having an upstanding supporting tubular member 26 which loosely receives therein a cooperative supporting shaft or rod member 27. The tubular member 26 has rows of holes 28 therein, said rows of holes having a location diametrically opposite each other. The rod member 27 has a circular groove 29 therein near its lower end. Use is made of a bolt 30 having a return bent end portion 31. The bolt 30 is receivable in a pair of holes 28 of the rows of holes with the portion 31 extending through a hole in one row and projecting into the groove 29. The lower end of the rod member 27 rests on the bolt 30. A nut 32 screwed on the bolt keeps it in place, and also enables the removal of the bolt at will for making vertical adjustments of the rod member 27 with respect to the base 25. When the bolt 30 is in place the portion 31 in the groove 29 prevents the rod member 27 from moving axially upward and allows the rod member to turn in the tubular member 26.

In order to mount the body 10 on the stand 11 for pivotal movement on a horizontal axis between the loading position and the discharging position, there are provided plates 33 which are secured to the body 10 exteriorly thereof between the ends of the body, and in spaced parallel relation to each other and parallel to the longitudinal axis of the body 10. The plates 33 each have a flange 34 which is riveted, welded or otherwise secured to the body 10, as at 35. The plates 33 each have three sets of holes 36, 37 and 38 therein. The upper end of the rod member 27 has a hub or the like 39. A bolt 40 extends through a selected pair of holes 36 of the sets of these holes and through the hub 39. The body 10 is thus connected with the stand 11 for pivotal movement. The body may be adjusted longitudinally by placing the bolt 40 in another pair of holes 36 as may be desired or required.

A pin 41 arranged in a selected pair of holes 37 in

the plates 33 will extend crosswise between the plates and thus be disposed to cooperate with the tubular member 26 to limit the movement of the body 10 into the desired discharging position. Likewise a pin 42 applied to selected holes 38 will limit the movement of the body 10 into the desired loading position. These pins 41 and 42 each may have a rubber sleeve to cushion severe shocks or jars which might be incurred through rough treatment or inadvertently dropping the body from the discharge to loading position. These sleeves also serve to eliminate noise upon contact with the member 26.

In order to counterbalance the body 10, so that the body may be given pivotal movement with minimum manual effort, there is provided a helical retractile spring 43 which has one end connected with the rod member 27 by a pivoted link 44 carried by the member 27, and the other end of the spring is connected with the body 10 by means of a short chain 45 on the spring and a hook 46 on the body 10. The spring 43 enables the empty body 10 to be brought into its loading position and to remain therein. The spring will be under tension and assist in the movement of the body 10 from the loading position into its discharging position when manual effort is applied to the handle 15. By reason of the links 20 of the chain 45 and the hook 46 the tension of the spring 43 may be varied in an obvious manner.

In lieu of the barbs 24 which are integral with the body 10, use may be made of barbed bands or strips such as those shown in Figs. 6 and 8. In Fig. 6, the strip 47 has upraised nodules 48 of hemispherical formation, each nodule having a barb 49. The barbs may be so arranged that when a plurality of strips 47 are applied to the body 10, the barbs will be disposed at proper angles with respect to the longitudinal axis of the body. Thus there will be small possibility of the bag being snagged or damaged by the barbs.

In Fig. 8 a cross-sectionally U shape strip 50 has barbs 51 cut from the material of one flange and the other flange 52 serves for securing the strip, to function in the manner as explained in connection with the strip 47.

In order to effectually handle bags of different size as to length, there is provided a separate ribbed end plate member 53 whose peripheral edge conforms to the cross-sectional shape of the body 10. The member 53 has radial studs 54 thereon which are received respectively in sets of holes 55 in the body, said holes being arranged in rows extending longitudinally of the body 10. The springiness of the material of the body 10 acting on the studs 54 in the selected holes 55 holds the member 53 in the desired position of adjustment. It is obvious that the member 53 serves as a false bottom for the container body 10 when it is in its loading position.

From the foregoing it will be understood that the container body 10 may be moved on a horizontal axis between an upright loading position and an inclined discharging position; that the body may be adjusted vertically with respect to the base; that the body may be adjusted as to proper angle for loading and discharging positions and in respect to center of gravity; that the spring counter-balances the weight of the machine body and assists gravity in holding the body 10 in discharge position and assists in maneuvering the body in the loading position; that the body may be turned about a vertical axis into different angular positions for more convenient loading of the bags or sacks and the discharge of the contents thereof; that the base 25 may be used as a wheel when the stand is thrown at an angle while holding the body 10, thus effecting a rolling means for easily transporting the machine from place to place; and that the other mentioned advantages may be attained.

It is further to be understood that the invention is not restricted to the details above described, but includes all constructions coming within the scope of the appended claims.

I claim:

1. In a bag emptying machine, substantially a hemi-cylindrical trough-like body adapted to contain a bag full of granular flowable material, and which supports said bag in a position so that the material may flow out of the open end of the bag, said body on its front end having a slidably mounted adjustable opening gate near which the open end of the bag may be disposed, the gate being slideable into a selective open position to enable outflow of the material from the bag, and slideable into a closed position to stop the outflow of the material, means mounting said body so that it may be rocked into and out of a tilted position, the rear end of said body having rearwardly diverging channels extending therefrom and communicating with the interior of the body for accommodating the usual ears or distentions on the bottom of the bag.

2. In a bag emptying machine, substantially a hemi-cylindrical trough-like body adapted to contain a bag full of granular flowable material, and which supports said bag in a position so that the material may flow out of the open end of the bag, said body on its front end having a slidably mounted adjustable opening gate near which the open end of the bag may be disposed, the gate being slideable into a selective open position to enable outflow of the material from the bag, and slideable into a closed position to stop the outflow of the material, means mounting said body so that it may be rocked into and out of a tilted position, a plate which conforms to the cross-sectional shape of the body when the plate is arranged crosswise therein, and means to retain said plate crosswise in different positions of adjustment with respect to said body to serve as a bottom rest for bags of different lengths.

3. In a bag emptying machine, substantially a hemi-cylindrical trough-like body adapted to contain a bag full of granular flowable material, and which supports said bag in a position so that the material may flow out of the open end of the bag, said body on its front end having a slidably mounted adjustable opening gate near which the open end of the bag may be disposed, the gate being slideable into a selective open position to enable outflow of the material from the bag, and slideable into a closed position to stop the outflow of the material, means mounting said body so that it may be rocked into and out of a tilted position, and means interconnected between said body and said gate operated by the movement of the gate to positively agitate the material to facilitate the outflow of the material from the body.

4. In a bag emptying machine, substantially a hemi-cylindrical trough-like body adapted to contain a bag full of granular flowable material, and which supports said bag in a position so that the material may flow out of the open end of the bag, said body on its front end having a slidably mounted adjustable opening gate near which the open end of the bag may be disposed, the gate being slideable into a selective open position to enable outflow of the material from the bag, and slideable into a closed position to stop the outflow of the material, means mounting said body so that it may be rocked into and out of a tilted position, and chains connected with the body and the gate operated by the movement of the gate which agitates the material to facilitate the outflow of the material from the body.

5. A bag emptying machine including a trough-like body for a bag full of flowable material, a stand, selectively adjustable cooperative means on the stand and said body mounting the body for pivotal movement on a horizontal axis between a substantially vertical loading position and an inclined discharge position, adjustment of the relative position of the elements forming said cooperative means enabling changes in the position of the horizontal axis with respect to said body, to adapt to different sizes and weights of bags and adjustment of the center of gravity of said body, said stand

embodying means for increasing or decreasing the height of the stand so as to raise or lower said body to adapt the machine to different sizes of containers into which the material is to be emptied and for proper and convenient loading of bags, said cooperative means comprising a pivot on the upper end of the stand, and bearings on said body, said bearings having rows of spaced holes therein, and said pivot being selectively engageable in selected holes of said rows, a retractile spring connected with the body and a stationary part of the machine, changing of the pivot point shifting the center of gravity of the body and when shifted to lighten the gravity load automatically increasing tension in the spring to facilitate moving the container to bag emptying position.

6. In a bag emptying machine, substantially a hemi-cylindrical trough-like body adapted to contain a bag full of granular flowable material, and which supports said bag in a position so that the material may flow out of the open end of the bag, said body on its front end having a slidably mounted adjustable opening gate near which the open end of the bag may be disposed, the gate being slideable into the selective open position to enable outflow of the material from the bag, and slideable into a closed position to stop the outflow of the material, means mounting said body so that it may be rocked into and out of a tilted position, the rear end of said body having rearwardly diverging channels extending beyond the longitudinal sides of the body and communicating with the interior of the body for accommodating the usual ears on the bottom of a bag, a central channel on the rear end of the body and a lifting handle interconnected across said central channel for strengthening the bottom.

7. In a bag emptying machine, substantially a hemi-cylindrical trough-like body adapted to contain a bag full of granular flowable material, and which supports said bag in a position so that the material may flow out of the open end of the bag, said body on its front end having a slidably mounted adjustable opening gate near which the open end of the bag may be disposed, the gate being slideable into a selective open position to enable outflow of the material from the bag, and slideable into a closed position to stop the outflow of the material, means mounting said body so that it may be rocked into and out of a tilted position, the rear end of said body having rearwardly diverging channels extending beyond the longitudinal sides of the body and communicating with the interior of the body for accommodating the usual ears on the bottom of a bag, a central channel on the rear end of the body and a lifting handle interconnected across said central channel for strengthening the bottom, said body having a plurality of spaced elevated portions on the interior thereof covering a substantial area of the bottom and sides of the trough, and raised directed projections on said elevated portions for engagement with and holding of said bag over a substantial area of the back and sides thereof during emptying.

8. In a bag emptying machine of the character described, a bag cradle of hemicylindrical shaped cross-section having a discharge spout and a rear end, a plurality of spaced elevated portions on the interior of said cradle covering a substantial area of the bottom and sides thereof, raised directed projections on said elevated portions for engagement with and holding of said bag over a substantial area of the back and sides thereof during emptying, said elevated portions comprising upraised nodules of hemispherical formation and having the raised projections thereon.

9. In a bag emptying machine of the character described, a bag cradle of hemicylindrical shaped cross-section having a discharge spout and a rear end, a plurality of spaced elevated portions on the interior of said cradle covering a substantial area of the bottom and sides thereof, raised directed projections on said elevated portions for engagement with and holding of said bag over a substantial area of the back and sides thereof dur-

ing emptying, said elevated portions comprising U-shaped strips having the raised projections cut from the material of one flange thereof and the other flange being secured to the body of said cradle.

10. In a bag emptying machine of the character described, a bag cradle comprising a single piece of material bent to hemicylindrical shape of smooth internal contour and having a tapering tubular spout on the forward end thereof, said spout having an upwardly and rearwardly slanting discharge opening, and a gate slidably and adjustably mounted over said opening for controlling material flow therefrom, chains having one end thereof connected to said body and their opposite ends connected to said gate whereby, upon movement of said gate, said chains agitate material being discharged from a bag and 15 providing a steady flow of material from said discharge opening, said chains also limiting movement of said gate.
